LOUVER CONSTRUCTION

Filed July 10, 1935

Fig. 2.

A cross-sectional view of a mechanical assembly. The assembly is contained within a rectangular frame (1). Inside, a horizontal plate (14) is supported by a central vertical post (12). A spring (9) is attached to the top of the post (12) and to a lever arm (10). A horizontal bar (13) is positioned above the plate (14). A series of vertical pins or supports (6) are arranged along the bottom of the frame (1). Numbered callouts point to various parts: 14, 13, 11, 12, 9, 10, 6, 15, 17, and 16.

LOUVER CONSTRUCTION

Emil A. Mader, Detroit, Mich., assignor of one-half to John Spargo, Detroit, Mich.

Application July 10, 1935, Serial No. 30,587

3 Claims. (Cl. 98—110)

This invention relates to louvers and particularly to louvers for ventilating purposes.

In mounting louvers to be opened by a current of air, it is usual to dispose them one above another and pivot them at their upper edges. The further that such louvers are swung open, under air pressure, the greater resistance is offered by their weight to opening travel. Such louvers are not adapted, therefore, to maintain their fully 10 opened positions responsive to a ventilating flow of air, but considerably obstruct such flow.

Also it has been generally necessary to form such ventilating louvers of aluminum, since a heavier and cheaper metal would entail too large 15 a gravity resistance to opening travel.

One object of the invention is to mount a set of louvers to turn on vertical axes, thus greatly reducing the resistance offered by their weight to opening travel, whereby they may be readily held 20 fully opened by the air flow, and whereby heavier, stronger, and cheaper material than aluminum may be practically employed.

Another object is to provide a set of pivotal louvers, connected for operation in unison, half 25 of which turn reversely to the other half, in opening or closing, whereby each group of louvers may limit opening travel of the other group, and whereby the effect on the louvers of gusts of wind, or of any whirl in a ventilating air flow is neutral- 30 ized.

A further object is to yieldably establish the closed position of a pivotal louver or shutter by a spring so connected to the louver as to exercise a maximum effect when the louver is closed and 35 a greatly reduced effect when the louver is opened.

Other objects are to adapt a set of louvers to be closed by a single spring, to provide a very simple regulation for the force exerted by such spring, 40 and to adapt the spring and its regulator to be compactly encased.

These and various other objects the invention attains by the construction hereinafter described, and illustrated in the accompanying drawing, 45 wherein:

Fig. 1 is an interior view of the louver construction, showing the louvers closed.

Fig. 2 is a horizontal sectional view of the same, taken on the line 2—2 of Fig. 1.

Fig. 3 is a fragmentary top plan view of a spring means for closing the louvers and a regulator for the spring, sectionally showing a casing for such means and regulator.

Fig. 4 is an elevational view of the same, again 55 showing the casing in section.

In these views, the reference character 1 designates a frame, constructed of angle bars and forming a rectangular opening. Installed in said frame and controlling the opening, is a set of pivotal, vertically elongated louvers 2, which will ordinarily be sheet metal but may be formed of glass if translucency is desirable. Each louver is secured at one longitudinal edge on a cylindrical rod 3 vertically journaled in the frame 1, the arrangement being such that the louvers at the 10 right side of the frame center are pivoted at their left hand edges, and those to the left of said center are pivoted at their right hand edges. Thus the two groups of louvers swing reversely, when both are operated to cover or uncover the frame 15 opening. To engage the louvers with their supporting rods 3, it is preferred to form them with marginal tubes or sleeves 4 wherein the rods are snugly inserted.

In the closed position of the louvers, the two 20 outermost ones seat upon sheet metal strips 5 of angular cross section which are interiorly secured to the frame and extend entirely around the opening thereof, and which serve as weather strips as well as seats for said louvers. Each of 25 the remaining louvers, when closed, seats against the pivotal edge of the adjacent louver of the same group, being conformed at its free edge to the sleeve 4 of such adjacent louver.

All of the louvers are interconnected to open 30 or close in unison by mounting a pair of intermeshed pinions 6 on the upper ends of the two centermost rods 3 and by connecting the louvers of each group by a swinging link bar 7, engaging brackets 8 secured to the inner faces of the 35 louvers. The link bars are so spaced from the louvers by said brackets, as to avoid interference with the louver travel.

A coiled spring 9 serves to effect closing of all 40 of the louvers when the flow of air through the frame 1 is cut off. Thus said spring extends from a suitable anchorage 10 to the free end of an arm 11 fast on the upper end of one of the two centermost rods 3, being increasingly tensioned as the louvers open. The effect of said spring on 45 the louvers, however, progressively decreases during their opening travel due to progressive diminution of the leverage afforded by the arm. This action of the spring is highly desirable, since it assures that the louvers will be firmly restrained from rattling when closed, and may be held fully opened by the minimum intended flow of air.

It is preferred, however, to provide a regulator for the spring to accurately adapt it to va- 55

rious air pressures. Thus the anchorage 10 may have the nature of a lever pivoted at its mid portion, one end of such lever anchoring the spring and the other pivotally mounting a nut 12 5 into which is threaded an adjusting screw 13. The head of said screw bears against a lug 14 in which the screw is freely rotative, said lug being bent up from one end of a sheet metal plate 15 surmounting the frame 1. The other end of said 10 plate may be bent up to form another lug 16 on which the lever 10 is pivoted. This arranges the pinions 6, spring 9, and the regulator for the spring in a compact group such as may be enclosed by a small sheet metal housing 17 fastened to the frame. 15

A narrow space formed between the pivotal edges of the two centermost louvers is suitably closed, preferably by a sheet metal member 18 which is rigidly secured at top and bottom to 20 the frame, and is folded upon itself to project forwardly into said space, its edges being oppositely bent inwardly of said louvers to overlap their pivotal margins (see Fig. 2).

Additionally to minimizing obstruction of the 25 frame opening in the open position of the louvers and to permitting the use of comparatively heavy sheet metal, the described construction eliminates any rattle of the louvers when closed. Such rattle has been a source of annoyance in louvers depending solely on gravity to maintain their closed 30 position.

It is a further considerable advantage of the improved louvers that they make practicable the installation of a variable speed fan-motor unit 35 to deliver the air current. Such a unit is, in many installations, desirable to accommodate the air current to varying temperatures or other conditions. Regulation of the spring 9 may be quickly effected to correspond with any variations of 40 the air flow.

Location of the spring regulator on the top of the frame renders said regulator conveniently ac-

cessible and avoids any obstruction by it of the air flow.

The invention is presented as including all such modifications and changes as come within the scope of the following claims. 5

What I claim is:

1. A louver construction comprising a frame having an opening for air flow, a pair of louvers controlling the opening, a pair of rods journaled in the frame and pivoting the louvers, a pair of intermeshed pinion members mounted on said rods and compelling reverse travel of the louvers in unison, a spring urging the louvers to their closed position, a regulator for the spring, and a housing mounted on frame and enclosing the 15 pinion members, spring, and regulator.

2. A louver construction comprising a frame having an opening for air flow, a closure for such opening, a member pivoting the closure in the frame and projecting exteriorly of the frame, an arm carried by said member in exterior proximity to the frame, a coiled spring connected at one end to said arm and urging the closure to its closed position, a lever pivoted upon the frame and forming an anchorage for the other end of the spring, the spring tension being regulable by adjustment of said lever, a nut pivotally attached to said lever, and a screw threaded in said nut and rotatively mounted on the frame for adjusting said lever. 25

3. A louver construction comprising a frame having an opening for air flow, a pair of pivotal louvers controlling the opening, a pair of intermeshed pinion members operatively connected to the louvers and compelling reverse travel of the louvers in unison, means yieldably urging the louvers to their closed position, a regulator for said means, and a housing mounted on frame and enclosing the pinion members, spring, and regulator. 35
